 werk Siemensstadt, near Berlin, Germany

Application June 14, 1935, Serial No. 26,558
 In Germany June 22, 1934

6 Claims. (Cl. 179—26)

This invention relates in general to an arrangement employing double operating switches in an automatic telephone system in which when the switch is used as a final selector an impulsive arrangement is connected up for the purpose of setting further numerical impulse switches which are accessible over the double operating switch.

More particularly the present invention consists in switching means that are associated with the double operating switch which, dependent upon the side of the trunk from which the seizing impulse is received and also the selected traffic direction, connects up switching devices for the transmission of trains of impulses over the selector.

The drawing shows one embodiment of the invention. It represents a private installation in which local connections between the subscribers N1 and N2 are set up in known manner over the call finder AS and the final selector LW. If the local subscriber N1 desires an exchange connection, then when he removes his receiver the call finder AS is set on to the line of the calling subscriber N1 in known manner. After this setting the subscriber is guarded by the short circuiting of winding II of relay C over contact 1c. For the purpose of setting up an exchange connection the final selector LW is set on to a particular contact over which relay An is energized. Relay An completes the following circuit for relay R: +, contacts 2an, 3s, relay R, —. Relay R closes a circuit for the rotary magnet DAW over +, relay interrupter RU, contacts 5c1, 6r, winding II of relay E, rotary magnet DAW, —. The rotary magnet DAW is operated by the relay interrupter RU until the following circuit, prepared by the opening of contact 1r and the closing of contact 8r, is completed over wiper d of the exchange selector AW: +, winding III of relay C1, contact 8r, wiper d of exchange selector AW, lead 9, wiper d of the call finder, relay P1, wiper d of the final selector, resistance W, —. Relay C1 operates in this circuit and by opening the circuit of magnet DAW at contact 5c1 brings the switch to rest. In the test circuit over wiper d of the exchange selector AW, relay P1 in the final selector LW also operates. Relay P1 in known manner which is not shown initiates the release of the final selector LW and the freeing of the call finder AS, whereupon relay C is released and removes the guarding at contact 1c. The following circuit can now become effective over wiper c of the exchange selector AW: +, contact 10c1, winding

I of relay C1, relay Pa, wiper c of exchange selector AW, lead 11, relay T, —. Relay C1 effects switching through at contacts 12c1 and 13c1 so that the following feed circuit is now completed for the subscriber N1: —, winding I of relay S, winding I of relay X, contact 12c1, wiper a, lead 14, over loop of the calling subscriber N1, lead 15, wiper b of exchange selector AW, contact 13c1, winding II of relay X, winding II of relay S, +. Only relay S operates in this circuit since relay X is a differential relay. By means of relay S the start circuit for relay R is interrupted at contact 3s. The calling subscriber is now connected to the exchange line AL. The impulse transmitted by the subscriber N1 are received by relay S and repeated to the exchange line AL at contact 16s.

Establishment of an incoming exchange connection

If an exchange call arrives over the exchange line AL relay A is energized by ringing current, and over: +, lamp L, contacts 17as, 18a, — connects up the lamp L. Relay H is also energized over: +, relay H, contact 18a, —, so that the following holding circuit is completed for the lamp L: lamp L, contact 17as, 19h, 20e, 21v1, —. Relay H locks up over: +, relay H, contacts 19h, 20e, 21v1, —. By the lighting of the lamp L the operator is notified of the incoming exchange call and therefore operates her speaking key momentarily after she has operated the switchhook HU. By the opening of contact 24ab and the closing of contact 22ab of the speaking key the following circuit is completed for relay AS: +, switchhook HU, contact 22ab of the speaking key, relay As, —. Over contact 23as the following locking circuit is completed for relay AS after the speaking key has been restored to normal: +, switchhook HU, contacts 24ab, 23as, relay AS, —. Relay AS at contact 17as interrupts the circuit for the lamp L. Over: +, contacts 45as1, 46as, 1r, wiper d of exchange selectors, in position O, winding I of relay E, —, relay E is energized and by opening its contact 20e interrupts the locking circuit for relay H so that relay H restores its contacts to normal. Relay AS opens contacts 25as and 26as and closes contacts 27as and 28as so that the operator's speaking set BA is connected to the calling exchange line AL and she can therefore ascertain the wishes of the calling exchange subscriber. In order to extend the exchange call to the desired local station the operator presses the connecting key whereupon relay VS is energized over con-

tact 29v. Relay VS closes a locking circuit for itself over: +, switchhook HU, contacts 24ab, 30vs, relay VS, —; relay VS also energizes relay AS1 over: +, switchhook HU, contacts 24ab, 30vs, 31vs, 32as, winding I of relay AS1, —. By the opening of contacts 33vs and 34vs and the closing of contacts 35vs and 36vs the operator's speaking set is transferred from the exchange line AL to the line 31/38. By the closing of contacts 39as1 and 40as1 the line 37/38 is connected with the wipers of the exchange selector AW of the calling exchange line AL. Relay AS1 at contact 45as1 opens the circuit for relay E. By the transfer of the exchange line AL to the line 37/38 relay J is energized over: +, winding II of relay J, contact 36vs, loop of the operator's speaking set BA, contact 35vs, winding I of relay J, —. The operator now manipulates her dial in her set whereupon relay J is energized corresponding to the transmitted digit. Relay J repeats the impulses to the rotary magnet DAW in the following circuit: +, switchhook HU, contacts 41j, 42vs, 43as, 44cl, winding II of relay E, rotary magnet DAW, —. During the impulses train relay E remains energized. At the end of the impulse train and the consequent release of relay E, the following test circuit is completed: +, contacts 47h, 48e, windings II and I of relay C1, relay P2, wiper c of switch AW, 25 lead 44, relay T, —. Relay P2 is not energized in this circuit. Relay C1 operates, however, and guards the called subscriber by short-circuiting winding II of relay C1 over contact 10cl. Relay C1 switches the exchange line through at contacts 12cl and 13cl. The subscriber N4 is now rung in known manner which is not shown. When the subscriber replies, relay S operates and switches the exchange line through at contact 16s. The operator now replaces her receiver and 40 thereupon opens the circuits for relays VS, AS, and AS1, whereupon these relays restore to normal. The exchange line is switched through at contacts 25as, and 26as and the exchange subscriber is now connected with the desired 45 local subscriber.

Extension of an incoming exchange call over a trunk line leading to a further exchange

If an exchange call arrives and the calling 50 exchange subscriber desires to speak to a subscriber of another exchange accessible over a trunk line VL, it is necessary that the exchange selector AW shall be set on to the trunk line VL. The setting of the switch takes place in the 55 manner already described for incoming calls. After the setting, however, relay P2 is energized as well as relay C1, and relay P2 closes the following circuit for relay D: +, relay D, contacts 49p2, 50as1, —. Relay D at contacts 51d completes an impulse bridge across the line 31/38 so that further impulses transmitted by the operator are repeated by dial contact 51j over the exchange selector to the trunk line VL and hence to the connecting devices connected to the trunk 60 line. These trains of impulses cannot affect the rotary magnet DAW since relay C1 is energized in the test circuit of the exchange selector and hence the circuit for the rotary magnet DAW is opened at contact 44cl. The relay S cannot be influenced by the trains of impulses transmitted 65 over the speaking leads by means of contact 52j since relay P2 has short circuited winding I of relay S over contact 53p2 and relay S is slow to release, and hence cannot be operated during 70 the interruptions at contact 52j. Since during 75

the setting over the trunk line VL relay AS1 remains energized independent of the operation of the key V1, the following circuit is completed by the relay P2 for the relay AS1: +, switchhook HU, contacts 24ab, 23as, 54p2, winding II of relay AS1, —. Relay AS1 therefore remains energized until the operator restores the switchhook to normal by replacing the handset.

It is therefore seen that devices are provided, particularly relay D, which dependent upon the 10 side of the trunk from which the seizing impulse is received (in the case of incoming connections from the exchange relay AS1 is energized), and the selected traffic direction (setting of the exchange selector on to the trunk line to cause the 15 energization of relay P2) connect up switching devices (impulse contact 52j) for the transmission of impulses over the selector.

Having described the invention, what is considered to be new and is desired to be protected 20 by Letters Patent will be set forth in the following claims.

What is claimed is:

1. In a telephone system, a sub-exchange, a 25 trunk line extending from a distant exchange connected to said sub-exchange, a selector switch in which said trunk line terminates, wipers on said selector switch having access to the subscribers' lines in said sub-exchange, a second trunk line extending to another exchange accessible to said selector switch wipers, means operated responsive to an outgoing trunk call to the distant exchange from a subscriber's line in the sub-exchange for operating said selector wipers as a finder to find the calling line and 30 connect it with the first trunk line, an operator's position for receiving incoming trunk calls from the distant exchange over said first trunk line, means controlled by said operator in answering an incoming trunk call from the distant exchange for operating said selector wipers to 35 connect said first trunk line with a subscriber's line, and means controlled by the operator in answering another incoming trunk call over said first trunk line from the distant exchange for 40 operating said selector wipers to connect said first trunk line with said second trunk line and extend the said other incoming trunk call to the 45 other exchange.

2. In a telephone system, a sub-exchange, sub- 50 subscribers' lines therein, a two-way trunk line extending from a distant exchange connected to said sub-exchange, a second trunk line extending to another exchange, a selector switch connected to said two-way trunk line, wipers on said 55 switch having access to said subscribers' lines and to said second trunk line, means responsive to an outgoing trunk call to the distant exchange from a subscriber's line for operating said selector switch as a finder to connect the calling line with 60 said two-way trunk line by way of said wipers, an operator's position connected to said two-way trunk line, means controlled by said operator in answering an incoming trunk call from the distant exchange over said two-way trunk line for a 65 subscriber for operating said selector switch to connect a subscriber with said two-way trunk by way of said wipers to complete the incoming trunk call from the distant exchange, and means controlled by the operator in case the incoming 70 trunk call is for the other exchange for operating said selector switch to connect with said second trunk line and extend the last incoming trunk call thereto over said wipers. 75

3. In a telephone system as claimed in claim 2, including impulse sending means at said operator's position, and means responsive to the connection of said two-way trunk line with said 5 second trunk line for automatically connecting said impulse sending means to said two-way trunk line.
4. In a telephone system as claimed in claim 2, including impulse sending means at said operator's position, means in said selector switch for automatically connecting said impulse sending means to said two-way trunk line in case a call is extended from said two-way trunk line to the second trunk line extending to the other exchange, said impulse sending means prevented from being connected to said two-way trunk line in case the selector switch is used as a finder to extend a call from a subscriber's line to the two-way trunk line.
- 10 5. In a telephone system, a sub-exchange having subscriber's lines therein, a selector switch, a two-way trunk line connected to said selector switch, a second trunk line connected to another exchange, means responsive to a call from a subscriber's line for operating said selector switch as a finder to connect the calling line with the 15 said two-way trunk line, an operator's position connected to said two-way trunk line, means controlled by said operator for operating said selector switch to connect an incoming call over said two-way trunk line with a called subscriber's line, means controlled by said operator for operating said selector switch to connect a call from said two-way trunk line to said second trunk line leading to said other exchange, and switching means in the selector switch depending 20 upon the type of call made for controlling the operation of said selector switch to connect with the desired traffic direction.
6. In a telephone system as claimed in claim 5, impulse sending means connected in said two-way trunk line to repeat impulses to said second trunk line, impulse repeating means in said two-way trunk line for repeating impulses in a call from a subscriber's line to said two-way trunk line, and means controlled by the operation of 25 said switching means for preventing the operation of said impulse repeating means when the call is extended from the two-way trunk line to said second trunk line.
